CLAIM

We claim the ornamental design for a water filtration pitcher, as shown and described.

DESCRIPTION

FIG. 1 is an upper left perspective view of a water filtration pitcher of the present invention;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is an upper left perspective view of a second embodiment of a water filtration pitcher of the present invention;

FIG. 9 is a front elevation view thereof;

FIG. 10 is a back elevation view thereof;

FIG. 11 is a left elevation view thereof;

FIG. 12 is a right elevation view thereof;

FIG. 13 is a top plan view thereof; and,

FIG. 14 is a bottom plan view thereof.

The broken lines in the drawing views represent unclaimed portions of a water filtration pitcher, which are included for the purpose of illustrating unclaimed environment only, and forms no part of the claimed design.
